UNITED STATES PATENT OFFICE.

GUSTAVE E. VILLARET, OF LEONIA, NEW JERSEY, ASSIGNOR TO HALCOLITE COMPANY, INC., A CORPORATION OF NEW YORK.

DESIGN FOR A FLAT PLATE FOR LIGHTING FIXTURES.

Application filed July 20, 1926. Serial No. 18,411. Term of patent 7 years.

To all whom it may concern:

Be it known that I, GUSTAVE E. VILLARET, a citizen of the United States, and a resident of Leonia, county of Bergen, and State of New Jersey, have invented a new, original, and ornamental Design for a Flat Plate for Lighting Fixtures, of which the following is a specification, reference being had to the accompanying drawing, forming a part hereof.

In these drawings: Figure 1 is an elevational view of the flat plate for lighting fixtures; and

Figure 2 is a diagrammatic edge view of the same.

I claim:

The ornamental design for a flat plate for lighting fixtures, substantially as shown.

GUSTAVE E. VILLARET.
